ELLIPSE GUIDE Frederick N. Lundebjerg, 4 Grassy Plain Terrace,
Bethel, Conn.Filed June 30, 1961, Ser. No. 121,055
4 Claims. (Cl. 33—30)

This invention relates to an ellipse guide to facilitate drawing of ellipses of different sizes and configurations. It has for an object to provide a device for drawing such ellipses which is of very simple construction and may be easily operated, as well as easily adjusted to draw ellipses of different sizes and different proportions of major and minor axes of the ellipses.

With the foregoing and other objects in view, I have devised the construction illustrated in the accompanying drawing forming a part of this specification. It is, however, understood the invention is not limited to the specific details of construction and arrangement shown, but may embody various changes and modifications within the scope of the invention.

In this drawing:

FIG. 1 is a side elevation of the device;

FIG. 2 is an end elevation looking from the right of FIG. 1;

FIG. 3 is a top plan view;

FIG. 4 is a detail longitudinal section of the support for the marking implement;

FIG. 5 is a partial side elevation and partial section of the upper part of the upright member and the guide disc;

FIG. 6 is a plan view of the guide disc and its support, and

FIG. 7 is a detail section of the guide disc and its support.

The device is a drafting instrument for drawing ellipses of different configurations and sizes. It comprises an upright tubular member or post 10 provided with a centering or fixed locating means 11 at its lower end, in the form shown comprising a point arranged to pierce a piece of paper or other material on which the ellipse is to be drawn. Above this lower end is a fixed collar or flange 12 above which is a bearing 13 for a horizontal bar 14, the bearing connecting the bar to the upright member or post so that it may be turned in a horizontal plane about this upright member.

Within the upper hollow portion of the tubular upright 10 is an upright elongated adjustable feed screw 15, connected at its upper end to an adjusting knob 16 in the form of a finger grip adapted to turn on a fixed washer 17 resting on the top of the member 10. The member 10 is provided in its opposite side walls with longitudinal guide slots 18 and 19, and is embraced by an elongated opening 20 in guide disc 21. This disc is preferably circular in shape, but could be oblong or other shapes, if desired. It is supported for adjustment by the screw 15 by means of a center bearing ring or collar 22 threaded on the screw 15, and supported by integral oppositely extending pivot pins 23 journaled in the disc 21 at the opposite sides of the opening 20. This support for the disc permits the disc to be tipped to various angles to the horizontal about the pivotal support 23.

Means is provided for connecting one edge of the disc to the upright member 10. In the arrangement shown, this comprises a wire or bar 24 pivotally connected at its opposite ends as at 25 to the washer 17 and at its lower end at 26 to the edge of the disc 21. It will be seen that by cooperation of this link and the threaded connection 22 of the disc to the adjusting screw 15, rotation of the screw will adjust the ring 22 up or down, and thus vary the angle which the disc 21 has with the horizontal plane.

2

The horizontal bar 14 is also a tubular member, and mounted for longitudinal sliding movement in this bar are supporting blocks 27 and 28. On top of the bar is a support 29 which may be a flat strip with downwardly turned ends 30 and 31 resting on top of the bar 14, and carried by this support are upright strips or pins 32 passing through the top portion of the support 29 and at their lower ends driven into the blocks 27 and 28 so as to be supported thereby. Carried by the members 32 is an adjusting screw 33 provided with a finger grip operating knob 34, this screw having bearing support at its opposite ends in the members 32.

Having threaded engagement with the screw 33 is an upright, downwardly extending bar 35 provided with a holder 36 in the form of means for gripping a lead or pen 37, or it could be a scribe. Thus this bar 35 and marking element forms a marking implement carried by the support 29 and adjustable longitudinally thereon toward and from the centering upright member 10, the element 35 and the marking means forming a depending marking implement that is guided for longitudinal movement by passing through an elongated slot 38 in the support 29, and further longitudinal slots 39 and 40 in the tubular bar 14. The member 35 may also have a guide flange or collar 35a at the under side of bar 14. The upper slot 39 also provides guide means for the elements 32. An upright guide, in the present case in the form of an upright bar 41, is connected to the support 29 at its forward end, as indicated at 42, and this is in position to engage the rim or edge of the guide disc 21 and of a length to engage this edge at various heights to which the disc 21 may be adjusted in the upright post or member 10, and it is held in engagement with the edge of the disc by a coil spring 43 connected to the guide 41 and to the upright member 10 by any suitable means, such as the collar 44. The spring is thus biased to hold the guide 41 in engagement with the disc during the rotating or turning movement of the bar 14 in drawing the ellipse.

It will be seen that when the pointed end 11 of the upright member or post 10 is anchored in a piece of paper or other material on which it is desired to draw an ellipse, the member 10 is held in an upright position and the bar 14 carrying the marking implement 37 may be rotated about this upright, the guide 41 being held against the edge of the disc 21 during this turning movement by means of the spring 43. The proportion of the major and minor axes of the ellipse will be determined by the angle at which the disc 21 is adjusted to the horizontal. If it is horizontal or parallel to the paper the figure will be a circle if the disc is circular, but if inclined, as shown in FIGS. 1 and 2, the figure will be an ellipse, and as indicated, the relative lengths of the major and minor axes will depend on the angle of inclination of this disc; the greater the inclination, the shorter will be the minor axis. The size of the ellipse will be determined by the distance between the centering means 11 and the marking means 37, which may be adjusted by the screw 33.

There may be a scale or indicator 45 on the side of the upright member 10 over which a pointer 46 on the ring 22 or pivot may slide to indicate the adjustment of this ring and the angular position of the disc 21. Similarly, a scale 47 may be provided on the member 29 cooperating with a pointer 48 on the depending member 35 to indicate the distance or adjustment of the marking member 37 from the center 11. This will determine the size of the ellipse drawn by the marking means as the bar 14 is rotated about the upright member 10.

It will be clear from the above that the device is of very simple construction, involving a small number of parts, and that it may be easily and quickly set to produce the desired size and shape of the ellipse to be drawn. As the supporting member 10 is in a vertical

upright position, and the marking implement supporting bar 14 extends laterally from it in a horizontal plane, the marking means 37 has a uniform bearing on the surface of the paper for the complete revolution of the bar, giving a uniform line for the entire ellipse.

Having thus set forth the nature of my invention, I claim:

1. An ellipse guide comprising an upright member having vertical guide means and provided with a centering means at the lower end thereof and a bearing above said lower end, a horizontal bar mounted on said bearing to rotate about said upright member, a support mounted on said bar for longitudinal movement thereon, a depending marking implement mounted for longitudinal adjustment on the support, an adjusting screw on the support having threaded connection with the marking implement for shifting it on the support, a guide disc, transverse pivot means for the disc mounted in said vertical guide means on the upright member, means pivotally connecting one edge of the disc to said member, means for shifting the pivot means longitudinally of the upright member to vary the angular position of the disc on said pivot means, a guide means on the support engaging the edge of the disc, and spring means connected to the support resiliently retaining the guide means in contact with the edge of the disc.

2. An ellipse guide comprising an upright tubular member provided with longitudinal guide slots in side walls thereof, a guide disc provided with an opening embracing the upright member, a transverse pivot means for the disc extending transversely of the upright member through said slots, means connecting one edge of the disc to the upright member, a screw in the upright member having threaded connection with said pivot means to shift it longitudinally of the upright member to adjust the disc to different angular positions, means for operating the screw, a horizontal bar pivoted at one end to the upright member to turn about said member, a support mounted for longitudinal movement on the bar, a depending marking implement carried by the support, a guide on the support engaging the edge of the disc, and spring means connected between the support and the upright member to retain the guide against the edge of the disc.

3. An ellipse guide comprising an upright tubular member provided with longitudinal guide slots in side walls thereof, a guide disc provided with an opening embracing the upright member, a transverse pivot means for the disc extending transversely of the upright member through said slots, means connecting one edge of the disc to the

upright member, a screw in the upright member having threaded connection with said pivot means to shift it longitudinally of the upright member to adjust the disc to different angular positions and provided with an operating finger grip at the upper end of the upright member, a horizontal bar, a bearing connecting one end of the bar to the upright member for turning movements of the bar about said member, said bar provided with longitudinal track means, a support means in said track means, an adjusting screw on the support means, a depending marking implement threaded on the adjusting screw for adjustment on the support means, a guide means on the support means engaging the edge of the disc, and spring means connected between the support means and the upright member and retaining the guide means in engagement with the edge of the disc during turning movements of the bar.

4. An ellipse guide comprising an upright member provided with longitudinal guide means and a centering means at its lower end, a guide disc provided with an opening embracing said member, a transverse pivot means for the disc mounted in said guide means, means connecting one edge of the disc with the upright member, a screw mounted in the upright member and having threaded connection with said pivot means to shift it longitudinally of the upright member to adjust the disc to different angular positions, a horizontal tubular bar, a bearing connecting one end of the bar to the upright member for turning movements of the bar about said member, a longitudinally slidable element in said tubular bar means, a support carried by said slidable element, a depending marking implement mounted for longitudinal adjustment relative to said support, an adjusting screw connected to the marking implement for shifting it relative to the support, a guide element on the support engaging the edge of the disc, and spring means interconnecting the support and the upright member and biased to shift the support toward the upright member to retain the guide element in engagement with the disc during turning movements of the bar about the upright member.
